UNITED STATES PATENT OFFICE

HARRY LERNER, OF BROOKLYN, NEW YORK

COVER HOLDER

Application filed March 1, 1928. Serial No. 258,183.

This invention relates to cover-holders for utensils having separate covers. It has for its chief object to provide a device which will be attachable to the top of the utensil in such a way that it can hold the cover, when the cover is off the top, near or associated with the utensil, yet entirely out of the way of the person serving from the utensil, and in a position where it cannot come into contact with the table or table-cloth.

It is a further object of the present invention to provide an article of this nature which may be made from a single strip of inexpensive resilient sheet-material,—such as brass—by a few simple stamping operations.

A further object of the invention is to provide an article of the class described which may be attractively finished by silver or nickel plating to present the appearance of other table ware and which may be readily washed, polished and otherwise handled in the same manner.

A few typical forms of the invention will be described in conjunction with the accompanying drawings, but the invention is limited only by the scope of the subjoined claims.

In these drawings:

Fig. 1 is a perspective of a casserole or the like having a separate cover associated therewith by the article of the present invention, the casserole-frame not being shown;

Fig. 2 is a detailed sectional view along line 2—2 of Fig. 1;

Fig. 3 is a perspective of the article of the present invention removed from the vessel;

Fig. 4 is a plan view of a blank from which the article can be made;

Fig. 5 is a detailed sectional view of a vessel having a modified cover-holder;

Fig. 6 is a perspective of this cover holder;

Fig. 7 is a detailed sectional view of a vessel having another form of the cover-holder of the present invention, and

Fig. 8 is a perspective of the cover-holder.

Referring more in detail to the parts of the drawings by reference numerals, the main body 1 of the vessel has a cover 2 which is an entirely separate article therefrom. In using such vessels, the person serving removes the cover 2, and, to get it out of the

way while serving from the dish, usually lays it alongside the dish on the table. Thus the cover is usually in the way of something else on the table, and what is more important, being usually covered with condensed vapors from the contents of the dish and sometimes with the contents themselves, it drips on the cloth and spots it, or smears it, in either case damaging the cloth or table.

The present invention contemplates 60 remedying this situation by means of such an article as that designated by A in Fig. 1. This device can readily be attached, by a formation thereof, such as 3—here shown as a pair of converging spring-jaws 4—4'—over 65 any projecting edge of the vessel. Since most casseroles and the like, are made with horizontally extending lifting-handles, such as 5, the article is usually made to be sprung onto one of these horizontal handles.

Another portion of the article A is formed into a holder or rack 6 for holding the cover 2 in association with the utensil, open and out of the way of the user, and preferably in the substantially vertical position shown. 75 This portion 6 can consist of a pair of coacting spring-jaws 7—7', which are formed from a continuation of the upper jaw 4 of the attaching portion 3. This rack portion 6 releasably but firmly engages the rim of the 80 cover, as shown, and serves to hold it securely and safely out of contact with the table cloth and out of the way of the person serving. It is obvious that it also provides a regular, convenient location for disposing 85 of the lid while serving, instead of having to find a location for the cover on the table every time it is removed.

The article of the present invention is 90 adapted to be quickly and cheaply made, in a few simple pressing operations, from a blank such as 8, which consists of a single strip of resilient-material, spring brass for example. One end of the blank 8 is shaped into the attaching-clamp portion 3, and the rest of the blank is bent up into a prolongation 9 of the upper jaw of the clamp 4, as shown in Fig. 3. 95 This prolongation 9 is bent downwardly at any desired point, such as 10,—depending upon the size of the rack desired, to form a 100

spring joint thereat, which joint insures a flexible and yielding rest for the lid.

The downward continuation 10 of the blank is interrupted as at 11, where the strip is bent horizontally but at an angle to the jaw 4, to thereby provide a spring-cushion seat 11 for the edge of the cover. The rest of the strip is bent upwardly at a suitable point 12,— depending upon the width of the cover it is to be used with,—to form the outer jaw 7' of the cover-holding clamp.

It is not essential that the base 11 of the cover-holding clamp be out of contact with the upper wall 4 of the lid-engaging clamp, but it is desirable in order that both bends 11 and 10, of the clamp may yield when the clamp is opened, thereby permitting a stiffer metal to be used than would be satisfactory if the bending were confined to the outer jaw 7'.

The handles and lid rims of the most widely used types of casseroles and the like are made of a standard fixed thickness, hence a single standard size of holder, such as that shown in Figs. 1-4, to correspond will have a wide field of usefulness, but of course the article may be made with the clamp and lid holder of different sizes and at different angles with respect to each other to fit the handles or rims and to hold the covers of other forms of dishes and vessels.

Another embodiment of the same inventive idea is shown in Figs. 5 and 6, where the blank of resilient elastic material is given a slightly different form, by bending downwardly on an upper edge of the rack portion to form a clamping portion 20 to fit over a narrower projection on the vessel—such as the rim of the guard 21, and the rack portion 22 is formed to open upwardly when so attached. This form of holder is just as well adapted to general use with vessels as is the other, and perhaps more so, due to its clamping a fixed-size guard member, 21.

In Figs. 7 and 8 there is shown a cover-holder adapted for service with all forms of vessel-guards, and it comprises a rack portion 33 having one of its jaws 34 bent downwardly and then shaped to fit against the guard-member 21 near its rim, where it can be attached in any suitable manner but preferably by soldering or riveting.

It is clear that this holder will do for any size or shape of vessel or guard, and though very simple and made of only one piece of sheet-material, is nevertheless almost indispensable for vessels having separate covers.

I claim:

1. A cover holder for vessels having separate covers comprising a strip of springy sheet-material having a part thereof formed into a pair of spring jaws opening in one direction, one of said jaws being continued at right angles to itself, a bend in said continuation in a direction opposite to the original direction, and the rest of said strip from

said bend to the end of the strip being formed into a rack opening in a direction at right angles to the first pair of jaws.

2. A cover-holder for vessels having separate covers, comprising a strip of sheet-material bent upon itself at one end to form a pair of spring-jaws, one of the sides of said jaws being continued upwardly from the open end of the jaws, and the rest of the strip being bent on itself at the upper end of said continuation to form another pair of spring-jaws.

3. A cover-holder for vessels having separate covers, comprising a strip of sheet-material bent twice upon itself at one end to form a pair of spring-jaws, one of the sides of said jaws being continued upwardly from the open end of said jaws, and the rest of the strip being bent three times on itself from the upper end of said continuation to form another pair of spring-jaws.

4. A cover-holder for vessels having separate covers, comprising a strip of sheet-material bent twice upon itself at one end to form a pair of spring-jaws, one of the sides of said jaws being continued upwardly from the open end of said jaws in a plane substantially at right angles to the plane of said jaws, and the rest of the strip being bent thrice on itself from the upper end of said continuation to form another pair of spring-jaws.

5. A cover-holder for vessels having separate covers, comprising a strip of sheet-material bent upon itself at one end to form a pair of spring-jaws, one of the sides of said bent portion being continued upwardly from the open end of the jaws, and the rest of the strip being bent on itself from the upper end of said continuation downwardly towards said jaws to form a second pair of spring-jaws, the bottom of said second pair of jaws contacting at one portion with the first jaws and sloping upwardly and outwardly therefrom out of contact with the first pair of jaws.

6. The method of making utensil-lid holders of the class described, comprising taking a strip of resilient sheet material, cutting off one end on a curved line, pressing said end inwardly over the rest of the blank successively about two transversely spaced lines thereof, pressing the rest of the strip as a whole in a direction substantially at right angles to the first direction, and pressing the remaining flat portion of said strip about three transversely spaced lines thereof, successively towards said first portion, substantially parallel thereto, and then upwardly away therefrom.

In testimony whereof I affix my signature.
HARRY LERNER.
